1 Claim

ABSTRACT OF THE DISCLOSURE

Compounds of fluorine, nitrogen, and oxygen, namely, nitrosyl trifluoride, fluoryldifluoroamine, nitronium difluoride, and tetrafluorodinitrogen oxide. The compounds are useful as oxidizers in rocket propellant systems.

This invention relates to novel compounds of fluorine, nitrogen and oxygen useful, inter alia, as oxidizers in rocket propellant systems. More specifically, the invention relates to nitrosyl trifluoride, NOF_3 ; fluoryldifluoroamine, F_2NOF ; nitronium difluoride, NO_2NF_2 ; and tetrafluorodinitrogen oxide (NF_2O_2).

For many years, hydrogen and fluorine have been recognized as the most powerful available combination among the possible chemical propellant systems. The unfavorable physical characteristics and extreme reactivity of hydrogen and fluorine have presented formidable obstacles to the effective utilization thereof in large rockets. Both elements must be stored as dangerous gases under high pressure, and must be liquified at a very low temperature and handled as boiling liquids during loading and flight. Compromise systems with lower performance have been used to avoid some of these practical difficulties.

Hydrogen-like fuels such as the hydrocarbons, ammonia, and hydrazines, have provided significantly better density, handling, and storage characteristics than hydrogen, while retaining fairly good specific impulse with some oxidizers. However, no fluorine-based oxidizers are known to have been used, except perhaps in small experiments. Instead, other oxidizers have been substituted. Liquid oxygen, which seems to be the most effective oxidizer now in use, provides specific impulses five to fifteen percent lower than fluorine in a comparable system. This sacrifice in performance does not actually give a major advantage in physical characteristics important for rocket design, or for oxidizer storage, since fluorine and oxygen have essentially the same boiling points, critical constants, and densities. The principal advantages for oxygen seem only to be easier manufacture and somewhat lower hazard in ground handling. Other currently known oxidizers with better physical properties than either fluorine or oxygen give appreciably poorer performance.

As rockets become larger, their missions more ambitious, the logistic and design problems resulting from the properties of fluorine or oxygen become much more difficult. At the same time, the need to use an oxidizer giving very high energy release becomes imperative. It is, therefore, appropriate to seek an oxidizer which has better physical characteristics than either fluorine or oxygen, but retains oxidizing power approaching that of fluorine itself.

It is accordingly a primary object of this invention to provide novel oxidizers which are essentially compounds of fluorine, oxygen and nitrogen and which may be practically utilized in propellant systems to provide essentially all of the advantages which attend the use of oxygen or fluorine per se.

It is an additional primary object of the invention to provide novel compounds of fluorine, oxygen and nitrogen in combination with fuels requisite to provide complete rocket fuel systems.

2

It is a specific object of the invention to provide the novel compounds nitrosyl trifluoride, NOF_3 , fluoryldifluoroamine, F_2NOF , nitronium difluoride, NO_2NF_2 , and tetrafluorodinitrogen oxide, $(\text{NF}_2)_2\text{O}$.

Nitrosyl trifluoride is prepared by reaction between nitrogen trifluoride and either ozonized oxygen or nitrous oxide in the presence of a glow discharge. Theoretically the reactions proceed as follows:

Temperatures of at least -100°C . and preferably from about -100°C . to about -200°C . are preferred when ozonized oxygen is employed. Pressure of at least about 0.1 mm. Hg, preferably from about one to about 600 mm. Hg, is employed.

Nitrogen trifluoride is preferably employed in at least stoichiometric quantities. Preferably the molar proportions of nitrogen trifluoride to oxygen containing reactant fall in the range of about 1:1 to about 5:1.

EXAMPLE I

Nitrogen trifluoride, NF_3 , and oxygen are reacted at a temperature -163°C . and a pressure of 40 mm. Hg in the presence of a glow discharge. The partial pressure of NF_3 in the system is maintained at about 20 mm. Hg, and the partial pressure of oxygen is allowed to fall until it has been largely consumed to form nitrosyl fluoride via intermediate conversion to ozone. Nitrosyl trifluoride condenses and is isolated from the reaction products by conventional means such as distillation.

EXAMPLE II

Nitrogen trifluoride and nitrous oxide in proportions stoichiometrically requisite to respond to the reaction indicated by Equation 2 are reacted in the presence of a glow discharge at a temperature of about -20°C . and a pressure of about 30 mm. Hg. The nitrosyl trifluoride, NOF_3 , is separated from the nitrogen byproducts by chilling the gas stream to about -140°C .

A propellant system including nitrosyl trifluoride is appropriately formed from a combination of nitrosyl trifluoride and ammonia, there being present in such a system at least about 0.24 part by weight of the fuel for each part of oxidant.

Fluoryldifluoroamine, F_2NOF , is prepared by the reaction in the presence of a glow discharge between tetrafluorohydrazine, N_2F_4 , and oxygen monofluoride, O_2F_2 , in accordance with Equation 3.

The reaction is appropriately effected at a temperature of from about -200°C . to about -100°C . and a pressure of from about 1 mm. Hg to about 500 mm. Hg. At least a stoichiometric amount of N_2F_4 is utilized. Preferred proportions of reactants comprise a stoichiometric excess of N_2F_4 of from about 10 to about 50 percent.

EXAMPLE III

Liquid tetrafluorohydrazine is cooled to -135°C . in a vessel equipped with discharge electrodes in the vapor space. Oxygen and fluorine are admitted to the vapor space in amount sufficient to maintain a partial pressure of about 10 mm. Hg of each gas. Glow discharge is maintained until the reaction is complete or nearly so, as indicated by decrease in pressure. Oxygen monofluoride, O_2F_2 , is first formed and reacts with tetrafluorohydrazine to provide as the reaction product fluoryldifluoroamine, F_2NOF , which is isolated from the reaction product mixture.

Alternatively, fluoryldifluoroamine may be prepared by the reaction between F_2NH in the liquid state and oxygen difluoride in the gaseous state at a temperature of at least

about -60° C. , preferably at a temperature of from about -60° C. to about -130° C. , but not colder than -150° C. In this alternative procedure a glow discharge is not required. The reaction may be indicated as shown by Equation 4.

EXAMPLE IV

F_2NH in the liquid phase is placed in a suitable reaction vessel and maintained at a temperature of about -60° C. Oxygen difluoride, OF_2 , is passed into the reaction vessel to provide a liquid reaction product comprising fluoryl-difluoramine and hydrogen fluoride in accordance with Equation 4. Nitrogen trifluoride, NF_3 , oxygen and nitrosyl fluoride, NOF , are formed as by-products.

Nitronium difluoramide, NO_2NF_2 , is prepared by the reaction of nitrogen oxides such as N_2O_4 or N_2O_5 with tetrafluorohydrazine or nitrogen trifluoride as indicated by the following equations.

In completing the reactions indicated by Equations 5, 6, 7, and 8, the nitrogen oxides are maintained in a condensed state in a suitable reaction vessel and tetrafluorohydrazine or nitrogen trifluoride is passed into the reaction vessel in the manner generally described in Example IV, the temperature being such as to maintain the nitrogen oxides in the liquid phase, that is to say at a temperature below 21° C. when N_2O_4 is utilized, or at a temperature below 32° C. when N_2O_5 is utilized. Nitrosyl fluoride, NOF , is a by-product of all reactions.

EXAMPLE V

N_2O_4 is charged into a reaction vessel maintained at a temperature of about 0° C. Tetrafluorohydrazine, N_2F_4 , is passed into the liquid N_2O_4 in the reaction vessel to provide nitroniumdifluoramide, NO_2NF_2 , as shown in Equation 5.

EXAMPLE VI

Example V is repeated with the exception that nitrogentrifluoride, NF_3 , is utilized in lieu of tetrafluorohydrazine to provide nitroniumdifluoramide as shown in Equation 7.

EXAMPLE VII

N_2O_5 in the solid form is charged into a reaction vessel maintained at 0° C. Tetrafluorohydrazine is introduced into this reaction vessel to provide nitronium difluoramide as a reaction product in accordance with Equation 6.

EXAMPLE VIII

Example VII is repeated with the exception that nitrogenfluoride, NF_3 , is utilized in lieu of tetrafluorohydrazine, N_2F_4 , to produce nitronium difluoramide in accordance with Equation 8.

Tetrafluorodinitrogen oxide (NF_2)₂O is prepared by the reaction between tetrafluorohydrazine and nitrous oxide in accordance with Equation 9.

EXAMPLE IX

Nitrous oxide, N_2O , and tetrafluorohydrazine are co-mingled at atmospheric pressure in the presence of a trans-

ition group catalyst, specifically platinum, at room temperature to provide tetrafluorodinitrogen oxide as shown in Equation 9. The by-products produced include nitrogen trifluoride, NF_3 , and nitrosyl fluoride, NOF . The formation of by-products may be minimized by increasing the pressure. Preferably, the reaction is effected at a pressure from about 10 to about 50 pounds per square inch and a temperature of about -50° C. to about $+70^{\circ}\text{ C.}$ Catalysts other than platinum which may be used include palladium, nickel, and molybdenum.

Alternatively, tetrafluorodinitrogen oxide may be prepared by the reaction between difluorodiazine, $\text{FN}=\text{NF}$, and oxygen difluoride, OF_2 , as shown in Equation 10.

The reaction is preferably effected at a temperature of not greater than -100° C. , preferably at a temperature of from about -110° C. to about -150° C. , at a pressure of from about two to about 200 pounds per square inch.

Excess difluorodiazine is preferably utilized.

EXAMPLE X

Solid difluorodiazine, in excess of that stoichiometrically required by Equation 10, and liquid oxygen difluoride are reacted at a temperature of -140° C. under a pressure of 5 atmospheres to provide $(\text{NF}_2)_2\text{O}$ as shown in Equation 10.

The following table is representative of propellant systems including the various compounds contemplated by the present application, with various fuels. The carbonaceous fuels shown are chosen to have a favorable composition, with respect to carbon-hydrogen ratio, when oxidized by the compounds shown opposite them. However, the propellant systems contemplated in this application are not restricted to those tabulated. The compounds contemplated are capable of energetic reaction with any fuel, the choice and proportion of fuel for each system being governed by consideration of flame temperature, average molecular weight of combustion products, and density.

Table I

Oxidizer:	Fuel
NOF_3 or F_2NOF	NH_3
NOF_3 or F_2NOF	N_2H_4
NOF_3 or F_2NOF	$(\text{NH}_2\text{CH}_2\text{CH}_2)_2\text{NH}$
NO_2NF_2	Alkanes
NO_2NF_2	NH_3
$(\text{NF}_2)_2\text{O}$	$(\text{CH}_3)_2\text{NNH}_2$
$(\text{NF}_2)_2\text{O}$	$\text{NH}_2\text{CH}_2\text{CH}_2\text{NH}_2$
$(\text{NF}_2)_2\text{O}$	N_2H_4

I claim:

1. The compound, NOF_3 .
